CLAIM

The ornamental design for a combined ski sharpener and brush, as shown and described.

DESCRIPTION

FIG. 1 is a left, front perspective view of a combined ski sharpener and brush showing my new design, with the brush member in a housed position;

FIG. 2 is a bottom plan view thereof;

FIG. 3 is a rear elevational view thereof;

FIG. 4 is a right, rear perspective view in an exploded condition; and

FIG. 5 is an end elevational view of the end opposite that shown in FIG. 4.

FIG.1

FIG.2

FIG.3

FIG.4

FIG.5
